UNITED STATES PATENT OFFICE.

NELSON P. HULST, OF MILWAUKEE, WISCONSIN.

SYSTEM OF DEVELOPING AND WORKING MINES.

SPECIFICATION forming part of Letters Patent No. 393,306, dated November 20, 1888.

Application filed December 14, 1885. Serial No. 185,595. (No model.)

To all whom it may concern:

Be it known that I, NELSON P. HULST, of Milwaukee, in the county of Milwaukee, and in the State of Wisconsin, have invented certain new and useful Improvements in Systems of Developing and Working Mines; and I do hereby declare that the following is a full, clear, and exact description thereof.

My invention relates to systems of developing and working mines; and it consists in a new method of exploitation in which rock filling is used to fill the spaces in the ore-bed exhausted of ore, all as will be fully set forth hereinafter.

In the drawings, Figure 1 is a general view showing a portion of a mine being developed by my system. Fig. 2 is a vertical section through a hoisting-shaft and its accompanying balanced cage-winzes on the line 2 2 of Figs. 4 and 5. Fig. 3 is a vertical longitudinal section through the ore of the ore-body, and also through the rock filling where it has replaced the ore, and bisecting a winze operated with balanced cages, its plane being at right angles to the plane of the section of Fig. 2 and on the line 3 3 of Figs. 4 and 5. Figs. 4 and 5 are horizontal sections on the lines 4 4 and 5 5, respectively, in Figs. 2 and 3.

My system is especially adapted for use in mines the highly-inclined walls of which are too wide apart and too soft or friable to permit the use of stull-timbers or pillars of ore to support them; and the object of my invention is to provide a more economical method of mining where rock filling has to be used than is at present in use, the economy being effected by reducing the large amount of "dead-work" required by using a single equipment only of tramways and cars, by avoiding the necessity of rehandling the ore and rock through specially-prepared chutes, as well as saving the expense of constructing said chutes and their accompanying ladder-ways, and, finally, dispensing with the trammimg of empty ore and rock cars, all of which disadvantages and expenses are entailed in mining by the ordinary ore and rock chute system.

My invention consists, primarily, in the combination of a hoisting-shaft with one or more winzes, each winze being equipped with balanced cages and having a continuous vertical series of framed end openings along two of its

opposite sides, which openings connect with timbered passage-ways (and these in turn with timbered cross-drifts) for cars, there being an opening for a car at an elevation of every eight feet, or thereabout, from bottom to top of the said winze.

In the several figures of the drawings, N represents the hanging wall of the mine, and O the foot wall.

P represents the ore in the ore-bed, and Q the rock filling which takes the place of the ore in the said bed when the ore is exhausted.

R R designate the balanced cages, and S is the hoisting-shaft.

1, 2, and 3 designate the drifts connecting the hoisting-shaft and winzes, there being only three levels shown in the present illustration, (although of course the number beyond two is immaterial,) and consequently there are only two winzes shown, which are marked W' and W'', respectively. These winzes are first sunk as small winzes from an upper to a lower drift, and then enlarged and completed by being built up in a timbered rock-filled pillar of about twenty feet width, reaching from the foot wall to the hanging wall of the ore-bed, and which partially fills a chamber excavated purposely for it. The portions of the excavated chamber outside of the rock-filled pillar form parallel spaces reaching from the foot wall to the hanging wall of the ore-body, between the plank and post walls of the said rock-filled pillar and the ore-walls of the excavated chamber on each side thereof, (between the points a b and c d in Figs. 3 and 4, from a to b being the original limits of the excavated chamber,) and in these parallel spaces the timbered passage-ways which are to serve the purpose of cross-drifts through the ore-body are built up, one above the other, as shown at p p in Fig. 3, the caps and sills of said timbering serving as horizontal braces to keep the rock-filled pillar securely in place.

In Fig. 2 a vertical central section of the rock-filled pillar Q' is shown, and in Figs. 4 and 5 horizontal sections of the same rock pillar Q' are shown, the plank and post side walls of which are indicated at their limits by the letters b b c c, designating the corners of said timbered walls.

In this method of working a mine it is de-

signed to win the ore from below upward. The hoisting-shaft S (shown in Fig. 2) in the hanging wall N is sunk to any desired depth. From a point near its bottom a drift, 1, is driven by shortest course to the ore-bed. At the point where it is designed to make another level above the bottom one a second drift, 2, is driven from the hoisting-shaft in the same transverse vertical plane as the lower drift or 15 level and well into the ore-bed. The lower drift, 1, as it is carried into the ore-bed, is widened out into a chamber having its roof about eight feet above its floor, and of a width sufficient for a pillar of rock about twenty feet wide to be built therein, while at the same time spaces will be left between the pillar of rock and the ore side walls of the chamber. These spaces, as also the rock pillar, must reach from the foot O to the hanging wall N, and the 20 width of the spaces must be sufficient to allow timber-work to be erected in them, as before described. From drift 2, at a point a few feet in the ore-body from the hanging wall, a small winze is sunk, making connection with the 25 chamber before mentioned, which winze, after completion of the rock pillar, becomes winze W'. In the floor of this chamber an excavation, E', is made vertically beneath the winze sunk from the level above. This excavation 30 is made of suitable size to accommodate the cages R to be used in the winze W', and of such a depth that the upper deck of the cages can be brought to the level of the floor of the chamber. Within the chamber the timber-work 35 is erected along both its side walls, making a continuous cross-draft or passage-way for tram-cars from foot to hanging wall. Through the middle of the chamber the timber-work of the drift from the hoisting-shaft is continued. 40 As it progresses into the chamber, the spaces between it and the side-wall cross-drifts or passage-ways are filled with rock, and rock also is filled into the remaining space of the chamber not occupied by the winze, which is built 45 up with timber from the bottom of the excavation E', before mentioned.

The timbering of the winze is carried up to the roof of the chamber, and is constructed to have open connection with the drift 1, leading 50 to the hoisting-shaft S, and also with the side-wall cross-drifts or passage-ways for the cars before mentioned. The filling with rock having been completed in this chamber, another chamber is excavated perpendicularly above 55 this first one and of the same dimensions. The excavation of this second chamber is begun and carried forward from the winze. The ore is removed through the winze and the drift 1 below connecting with the hoisting-shaft. The 60 rock and timber can be lowered by winze from the drift 2 above.

When the excavation of ore from this second chamber is completed, side-wall or cross-draft timbers are erected, as in the chamber below, 65 having their sills resting on the caps of the cross-draft timbers below. Rock is filled into the entire space of this chamber not occupied

by the cross-drifts p p and the timbering of the winze, which is also carried up to the roof of the chamber. This work of excavating 70 chambers, setting up cross-drifts therein, extending the winze-timbers to the roof, and filling the remaining space of the chamber with rock is repeated until the drift 2 above is reached. 75

In the chamber connecting with drift 2 the timber-work of said drift is continued as in the case of the chamber started from drift 1, in order to make a connection from the hoisting shaft with the winze W² tributary to this 80 level. It is shown in Fig. 2 in elevation, where 1 and W² are respectively drift 1 and its tributary winze, 2 and W² being drift 2 and its corresponding tributary winze.

The timbering of winze W² is extended 85 above drift 2, where it forms a chamber, E², designed to hold the machinery used to operate the balanced cages R of that winze. On the floor of the chamber below drift 2 the timber-work of winze W² is started (in a space, 90 E², left in the rock filling) and built up in this chamber just as a portion of winze W' was built below the floor of drift 1, and for the same purpose. The bottom of winze W² is located the same distance from the foot wall 95 as was the bottom of winze W'. Its middle line is in the same transverse vertical plane as that of the middle line of winze W'. Drift 3 is driven from the hoisting-shaft S in the same transverse vertical plane as drifts 1 and 2, and, as before, a winze is started from this level to connect vertically with the lower completed part of the winze W², started in the chamber just below drift 2. The work of building a 100 pillar of rock, with its inclosed winze and connecting cross-drifts, is repeated from drift 2 upward, just the same as described from drift 1 upward to drift 2, to a point where drift 3 is to be made, and so upward, as the work of mining ore demands. 105

In the working of a mine, however, by this method it will suffice that the building of a rock pillar and its accompanying winze and passage-ways or cross-drifts be carried forward in advance of the mining of ore to that 115 point only where delay and impediment to economical working of the mine will not be occasioned. Thus the pillar, &c., above drift 2 need be started only when the ore is well nigh exhausted between drifts 1 and 2. 120

Having opened or developed the mine by this system, we have a hoisting-shaft with its accompanying winzes and passage-ways connecting therewith, which crosscut the ore-body on both sides of the winze at every lift or elevation of eight feet, or thereabout. 125

To begin mining, the ore at the junction of the cross-drifts with the foot and hanging walls is first attacked and at the lowest point—i. e., the bottom of the lowest level.

Inasmuch as in the drawings I have represented the mining as being completed (by removal of the ore and substitution of the rock filling) from the lower level up to the point in-

dicated by the line C D, Figs. 2 and 3, in describing the operation of mining I will begin with Fig. 4, referring incidentally, for purpose of illustration, to the earlier figures, showing various stages of the work already accomplished in levels below the line on which Fig. 4 is taken. Fig. 4 represents a horizontal section of Fig. 2 on line 4 4 before mining has been carried above that point, and the points 5 designated by *a a d d* at the extremity of the cross-drifts would be where the ore above said line 4 4 should be first attacked. Enough of the timber-work of the passage ways or cross-drifts is first removed to uncover a small face 10 of ore, and longer posts are used to replace the posts thus removed, which serve to keep the plank side walls of the rock pillar secure. These longer posts well braced will give greater 15 security to the pillar. As fast as the ore is removed, thereby allowing room to move the tram-road away from the rock-filled pillar, this is done, and rock is filled in against the planking and posts which incase the rock pillar. As the mining progresses, the rock is 20 filled against the pillar until the filling reaches the passage-ways leading from the winze to the cross-drifts, (said passage-ways being shown at *e e* in Figs. 3, 4, and 5.) From the ends of these passage-ways farthest from the 25 winze the timber-work of a longitudinal drift is erected and continued outward in both directions (identical with the longitudinal drifts shown at *f f* in Figs. 3 and 5) toward the ever-receding face of ore which is being mined. 30 When the rock filling of the first lift or bench has been extended sufficiently to make it safe 35 to begin mining on the bench immediately above it, the work of mining is begun on the upper or second bench, commencing the attack 40 on the ore at same relative points as on first bench. Each bench has its longitudinal drift located vertically above the longitudinal drift below it. Two or more benches can thus be worked at the same time, as shown in Fig. 3, 45 the number possible to be worked being limited only by the capacity of the winze and its hoisting-shaft.

Fig. 3, as stated, shows a vertical section through these longitudinal drifts and the 50 winze, and in Fig. 5 one of these longitudinal drifts leading from winze W' is shown in plan. As is evident, by this system of working a mine, no drifting whatever is required after the pillar of rock is completed. The 55 progress of mining and filling with rock provides the longitudinal drifts required. The timber of the cross drifts used in the chambers can be immediately used in the longitudinal drifts built in the rock filling. It is obvious 60 that under some circumstances the rock-filled pillar may be built up in an excavated chamber directly against one side wall of said chamber, in which case, in place of the described parallel spaces on each side of the said rock-filled 65 pillar, there would be a space on one side only to receive the cross-drift or passage-way timbers *p p*, and similarly the described longitudi-

nal drifts would extend only from one side of the winze.

By the use of my balanced cages in the 70 winzes I am enabled to lower the ore as mined to the level of the first drift, so that it is on a plane with the bottom of the hoisting-shaft, and in so doing I utilize the superior weight of the descending ore to raise the rock, timber, &c., to the level from whence the ore was taken, this being a great saving of motive power, and a further advantage lies in the fact that the rock and timber from above and the ore from the mine are all delivered at the 80 same plane in the hoisting-shaft, thereby avoiding the trammimg of the same at different levels, the trammimg of empty cars and expensive rehandling of the said ore, rock, and timber. 85

In Fig. 1 I show various details of construction, which will be readily understood by those skilled in the art. This is a general view, wherein I have selected a part of winze W', designating its framed end openings by 90 the letters *g g* and next them the passage-ways *e e*, and then the cross-drifts *p p*, which latter are timbered by the horizontal braces *h h* and vertical posts *i i*, the planking next said posts being marked *k k*, and the rock-filled pillar between said plank and post side walls being marked *Q' Q'*. I also show a portion of the drift or level 2, representing that part which extends through the rock-filled pillar, and have 95 illustrated the manner of timbering said drift. 100 In addition, this figure shows the timbering of the winzes and various passage-ways in detail.

Having thus fully described my invention, which I claim as new, and desire to secure by 105 Letters Patent, is—

1. In a system of developing and working a mine, the combination of rock-filled pillars built within and partially filling an excavation in an ore-bed, for purpose of supporting the 110 foot and hanging walls of the ore-bed, having its sides properly secured by posts which are braced against the ore side walls of the excavated chamber, with a winze built in said pillar, substantially as shown and described. 115

2. In a system of developing and working a mine, the combination of rock-filled pillars and winzes inclosed therein, with a space on either or both sides of the pillars, which entirely crosscut the ore-bed, wherein timber-work of cross-drifts or passage-ways may be built contemporaneously with the construction of the pillar, substantially as shown and described. 120

3. In a system of developing and working a mine, the combination of a hoisting-shaft with one or more winzes, each winze being equipped with balanced cages, and having a continuous vertical series of framed openings in either or both ends for passage-ways for 125 ears, substantially as and for the purposes set forth.

4. In a system of developing and working a mine, a rock-filled pillar and drift-timbering or

- timbered cross-drifts or passages built or framed one above another in the open spaces between the rock-filled pillar and the ore side walls of the chamber containing the pillar, either contemporaneously with the construction of the pillar or when required, which cross-drifts are designed to connect with the openings for passage-way of cars arranged and provided in the end or ends of the winze contained in the pillar, substantially as set forth.
5. In a system of developing and working a mine, the combination of winzes, constructed substantially as described, with cross-drifts or

timbered spaces which serve for drifts, where-
by the driving of drifts required to develop 15
the mine is avoided, substantially as and for
the purpose set forth.

In testimony that I claim the foregoing I
have hereunto set my hand, at Milwaukee, in
the county of Milwaukee and State of Wis- 20
consin, in the presence of two witnesses.

NELSON P. HULST.
